[57] CLAIM

The ornamental design for an air cleaner or the like,
substantially as shown.

DESCRIPTION

FIG. 1 is a perspective view taken from the top, front
and left side of an air cleaner or the like showing our
new design;

FIG. 2 is a perspective view taken from the top, rear
and left side thereof;

FIG. 3 is left side elevational view of FIG. 2;

FIG. 4 is a top plan view of FIG. 2;

FIG. 5 is a front elevational view of FIG. 2;

FIG. 6 is a rear elevational view of FIG. 2;

FIG. 7 is a bottom plan view of FIG. 2; and

FIG. 8 is a right side elevational view thereof, showing
the cleaner housing rotated 90 degrees from the position
shown in FIG. 2.

FIG. 1

FIG. 2

FIG. 3

FIG. 5

FIG. 4

FIG. 6
